UNITED STATES PATENT OFFICE.

JOSEPH H. WEEKS, OF BATTLE CREEK, MICHIGAN, ASSIGNOR OF ONE-HALF TO JOSEPH W. BRYCE, OF BATTLE CREEK, MICHIGAN.

MEANS FOR RECORDING READINGS OF METERS.

1,242,093.

Specification of Letters Patent.

Patented Oct. 2, 1917.

Application filed March 22, 1916. Serial No. 85,823.

To all whom it may concern:

Be it known that I, JOSEPH H. WEEKS, a citizen of the United States, residing at Battle Creek, in the county of Calhoun and State of Michigan, have invented certain new and useful Improvements in Means for Recording Readings of Meters; and I hereby declare that the following is a full, clear, and exact description thereof, reference being had to the accompanying drawings, which form part of this specification.

This invention is a novel card record making machine for making visual and permanent records on cards or sheets of the readings of the register mechanism of gas and electric meters, dial registers, time registers, etc., and its object is to provide novel means by which single records or duplicate records can be taken from an ordinary meter register.

In the accompanying drawings I have illustrated one practical form of the invention and will explain same in detail with reference thereto, and set forth in the claims the novel features and combinations of parts for which protection is desired.

In said drawings:

Figure 1 is a top plan view partly broken away, of my novel card record making machine.

Fig. 2 is a rear view of Fig. 1 showing the parts in different positions by the aid of dotted lines.

Fig. 3 is a horizontal sectional view taken on the line 3-3 of Fig. 4.

Fig. 4 is a vertical sectional view taken on the line 4-4 of Fig. 1.

Fig. 5 is a vertical cross-sectional view taken on the line 5-5 of Fig. 1.

Fig. 6 is a view of one of the record cards detached, and

Fig. 7 is an enlarged detail section of one of the punching devices.

The registering mechanism from which the records are to be taken may be of any suitable kind, and is shown as having a "units" registering shaft 1, a "tens" registering shaft 1^a, and a "hundreds" registering shaft 1^b; which shafts are provided with intermeshing gears and pinions, that may be driven by gearing from a master shaft 1^c as indicated in Fig. 1. Such registering mechanism being of a well known

type, needs no specific description, and the particular construction thereof forms no 55 part of the present invention.

The master shaft 1^c is operatively connected in any suitable manner (not shown) with the proper actuating member of the meter or other mechanism whose operations 60 are to be registered.

Said registering mechanism is mounted in a movable frame composed of front and rear plates 2 and 2^a and side plates 2^b, which latter extend beyond the rear plate 2^a for 65 a purpose hereinafter explained. Said frame is slidably mounted within an outer casing 3 of any suitable construction which may be mounted within, or attached to the meter casing M, or any other suitable support. 70

The front of the casing 3 may be provided with an opening, opposite the face of the register and the disks 1^b, and said opening may be closed by a glass plate 3^b. 75

On the outer end of each shaft 1, 1^a and 1^b, is mounted a disk 1^b, and each disk is provided with a forwardly projecting perforating pin 1ⁱ (Figs. 4 and 7) which is adapted to punch the record cards or sheets R, r, 80 as hereinafter explained.

Each disk 1^b has in its periphery, which is preferably diametrically opposite the pin 1ⁱ, a notch 1^j for a purpose hereinafter explained. Fitted against the front plate 85 2 of the movable frame is a sliding plate 7 which has an opening large enough for the accommodation of the several disks 1^b and is movable vertically, being normally pressed upward by a spring 7^a. On the 90 lower side of the opening in the plate 7 are stop lugs 7^b which are adapted to engage the notches 1^j in the several disks as herein-after explained. The plate has upwardly extending fingers 7^c which have slots 7^d attached to part 2, and this plate 7 has on one end a beveled lug 7^e for a purpose hereinafter described. 95

Upon each pin 1ⁱ is preferably placed a compressible cushion 1^s, (see Fig. 7) which 100 may be of rubber, and which normally projects slightly beyond the point of the pin, and when the latter is forced into the card the cushion is compressed, but when the pin is moved away from the card the cushion 105 expands and clears the card from the pin.

The frames 2 and 3 should be relatively movable so that the punches 1^a can be advanced toward or from the glass plate 3^b for a purpose hereinafter explained. As shown, frame 2 is bodily movable; and for this purpose the side plates 2^b and the side walls of the casing 3 are provided, in rear of plate 2^a, with slots 2^c and 2^d through which pass the cam ends 4^a of a slide 4, said cam ends 4^a being so shaped that if the bar 4 is moved longitudinally the ends 4^a engaging the slots 2^c will move the frame 2 forward or back. The slide 4 is guided, and held against sidewise movement by a pair of strips 4^b secured on the undersides of the members 4^a and slidable within the slots 4^c formed in the sides of the outer casing 3 continuous with the slots 2^d.

The bar 4 may be reciprocated by means of a crank arm 5^a mounted on a rock shaft 5 journaled in bearings 3^m attached to the casing 3 as shown. The crank arm 5^a connects with the bar 4 by a connecting rod 5^x fitting on the pins 12 and 13 on said crank and bar respectively.

The shaft 5 is provided on its forward end with a segment 5^b and on the shaft beside the segment is loosely pivoted a lever 5^c which, when in normal position, lies horizontally upon the casing 3, as indicated in Figs. 1 and 2, and can be raised to practically vertical position, as indicated, without affecting the shaft 5; but when raised to such position the lever will contact a lug 5^d on segment 5^b, and a further movement of the lever 5^c to the right will rock shaft 5 and cause it, through crank 5^a and the connecting rod 5^x to move bar 4 to the left until the lever reaches the position indicated at 5^e, Fig. 2.

When the lever 5^c contacts the lug 5^d it is engaged by a catch 5^f attached to the segment 5^b, and shown as a spring-actuated ball catch adapted to engage a corresponding recess in the lever, so that when the lever 5^c is returned from the position indicated by dotted lines 5^e (Fig. 2) to the full line position shown, the lever will cause the segment 5^b to rock shaft 5 backward and move bar 4 to the right thus returning it to normal position; but when the lever 5^c reaches the vertical position (Fig. 2) segment 5^b engages a lug 3^g on the casing 3, and further return rocking movement of shaft 5 is prevented, but lever 5^c may forcibly disengage catch 5^f and be moved on down to the position shown as at 5^e in Fig. 2.

Slidably attached to plate 2 above the lug 7^e is a catch plate 8 which may be attached to plate 2 by means of slots and pins as indicated in Fig. 4; and this plate has a finger 8^a which is adapted to be projected outwardly under the end of the lever 5^c as indicated in Fig. 4; but when the plate 7 is

fully raised this plate will be retracted by the engagement of the bevel face of lug 7^e with the bevel face 8^b on the under side of the plate 8, see Fig. 4. The plate 7 cannot rise in such position as to disengage plate 8 until the notches 1^j in the several disks have been brought into register with the teeth 7^j, as hereinafter explained.

In the side of the sliding plate 8 is a notch 8^j which is engaged with an arm 11^a on top of a shaft 11 pivoted in ears on the plate 2^a, and on the lower end of this shaft is an arm 11^b to which is pivotally connected a catch 11^c which extends through an opening in the plate 2^a, and the end of this catch is adapted to engage a notch 4^x in the slide bar 4 and lock the latter when the slide 8 is fully retracted, but when the slide is projected by the insertion of a card to the position shown in Fig. 1 the arm 11^a will rock shaft 11 and withdraw catch 11^c from the bar 4^x, thus permitting the operation of the lever 5 as heretofore stated.

On the shaft 1^a may be mounted a cage gear wheel 1^b which is adapted to be engaged by a spur wheel 6 mounted on a stud 6^a attached to the upper end of a lever 6^b pivoted on a stud 6^c attached to the rear plate 2^a. On the stud 6^a is also pivoted a lever 6^d that may be provided with a spring catch or pawl 6^p adapted to engage serrations or notches 6^a in the spur wheel 6 when the lever 6^d is moved in one direction, so that the spur gear 6 may be rotated by oscillating lever 6^e. Said lever 6^e is provided on its outer end with a handle 6^r by which it can be operated from the front of the casing, and this arm 6^r is adapted to engage a notch 5^h in the lever 5^c, when the latter is lowered, and when so engaged will hold spur gear 6 out of mesh with the cage gear 1^b as shown in full lines in Fig. 2.

A locking lever A (Figs. 1, 2, 3) is adapted to hold gear 6 out of mesh with gear 1^b until the slide bar 4 is moved to the left its full stroke. A block O on slide bar 4 is adapted to come into contact with the top arm of lever A and move it to the upright position indicated by dotted lines in Fig. 2. The gear O^x brings gears 6 and 1^b into mesh.

The large gear O having a long hub (Fig. 1) is loosely mounted on shaft 1 between the collar, friction spring and the small pinion on shaft 1. Said collar and pinion being fast to shaft 1. The friction spring allows shaft 1, 1^a, 1^b to be turned back to zero without disturbing any of the other working parts.

For the purpose of recording the number 125 of the meter on the card by perforating the same a series of needles N mounted on a plunger and working through the plate S are adapted to be operated by a cam slotted lever P', whose cam-way p is engaged by 130

the pin p' mounted on the arm p^2 on the sliding bar 4. The cam lever P' is connected by a link L with the base or bearing member P^s of the plunger P , and said bearing portion is guided rectilinearly by the block P^4 working within the slot P^5 of the bottom casing wall. A plate P^6 carried by the guiding block holds the plunger elements in proper relative position for operation.

Removable registry cards or sheets R can be inserted between the glass 3^b and the registering mechanism, when the latter is retracted to the position shown in Fig. 1. Said cards may be guided by means of the plate S through which the disk 1^h projects, as shown in Figs. 1 and 3. For convenience in inserting and properly positioning the cards in the casing I prefer to cut away the lower right hand corner of the card as shown in Fig. 6.

On the cards R should be printed dials, as indicated, corresponding with the usual numeral dials (not shown) of the several pointers 1^h ; so that when a card R is properly inserted in position the printed dials on the card will be directly opposite the fingers 1^i ; and if the card is forcibly brought into contact with the pins 1^i it will be punctured by the latter; and when the card is removed the punctures therein (indicated at r^3 Fig. 6) will show the exact positions of the fingers 1^i in relation to their respective dials at the time of the puncturing operation.

Thus in the example shown in Fig. 6 the "hundreds" and "tens" pointers 1^h were each at 8; while the "units" pointer was at 3; so that the amount registered would read 883, (or 88300) assuming the reading was taken from an ordinary gas-meter register.

In order to make duplicate records, two cards or sheets may be simultaneously introduced and punctured. Preferably, as hereinafter explained, I introduce with the card a sheet, indicated at r , printed like the card R , and of the same size; this sheet is preferably of a different color from the card for a purpose hereinafter explained.

50 Operation.

To make a record of the amount registered by the meter, the lever 5^e is first raised to a perpendicular position (5^e Fig. 2) or until it is stopped by the lug 5^a on the side of segment 5^b ; this permits the catch 5^f to engage the lever.

A card R is then inserted behind the glass 3^b . The lever 5^e is then moved to the position $5^{e''}$ (Fig. 2) turning the shaft 5 and causing crank arm 5^a and connecting link 5^x to move bar 4 to the left, which will move casing 2 toward the card R , causing the pins 1^i and N to punch the card as indicated in Figs. 3 and 5. Then upon the return move-

ment of lever 5^e catch 5^f will cause segment 5^b to return shaft 5 and bar 4 to normal position. When lever 5^e has been returned to the position 5^e (Fig. 2) the card R should be removed. Then lever 6° should be operated manually to turn gear 6, and gear 1^u brings the register and punching pins back to zero position. Lever 5^e is then lowered to the first position, shown in dotted lines Fig. 2, closing the opening through which the card was inserted.

When a card is inserted its cut away corner will engage and force slide 8 outward, until its end 8^p projects under the squared end of lever 5^e , said lever being in the position shown by dotted lines 5^e in Figs. 2 and 4, and will prevent return of the lever until the register is reset.

The lever 6° is then operated manually to turn gear 6 and 1^u until the teeth 7^j on the plate 7 register with the notches 1^l . Then plate 7 is moved upward by the spring 7^a and locks the punching disks at zero. When plate 7 rises the lug 7^e contacts with the bevel part 8° of slide 8, and moves slide 8 back and releases lever 5^e , which can then be pressed down, and in descending said lever comes in contact with the upper ends of the lugs 7^b on plate 7 (which are bent toward the front or card opening as indicated in Fig. 1) and will force plate 7 down releasing the disks 1^h , and leaving them free to be turned by the registering wheels in the usual manner.

When the movable frame 2, 2^a and 2^b with members 8 , 8^a and 8^b located within it) is moved forward it will carry latch 11^e out of the notch in bar 4, but said latch will return to place when the stroke is finished. When lever 5^e is raised vertically the plate 7 is freed, so the spring 7^a raises plate 7 and brings one or more of the teeth against the periphery of the disks 1^h and holds said plate in that position until the three disks are in unison, or at zero (0). The end 8^a of slide 8 being under 5^e prevents the operator from closing the lever 5^e until he has turned the numeral disk back to zero.

In order to make a distinctive record, and at the same time make a duplicate record, a record sheet r , corresponding in size and appearance to card R , may be inserted with the card, as indicated in Figs. 1, 3 and 7. The sheet r may be different in color from the card, and when the pins 1^i are forced through the sheet and into the card, the pieces punched from the sheet are left in the card, as indicated in Fig. 7, and these punched pieces in the card show very distinctly the reading on the printed card dials, and the perforations in the sheet show the same reading. The number of the meter may be simultaneously indicated on both card and sheet by the puncturing needles N , as indicated at the middle point of the lower edge of Fig. 6. The card and sheet must and

will read alike as they are made at the same time, and when used for gas, or electric meter records, the cards can be filled with the company and the sheets sent to the consumers. The meter is preferably set back to zero after each puncturing operation so the cards will show the amounts registered between successive recording operations.

What I claim is:

- 10 1. In a recording device for registers, the combination of a casing, a registering mechanism therein, and punching devices connected with the registering devices, means for impaling a card upon said devices, and compressible cushions on the punching devices for clearing the punctured cards therefrom.
- 20 2. In a recording device for registers, the combination of a casing, a registering mechanism therein, and punching devices connected with the registering devices, means for supporting a removable card or sheet opposite said punching devices, means for impaling the card upon said devices, and compressible cushions on the punching devices for clearing the punctured cards therefrom.
- 30 3. In a recording device for registers, the combination of a casing, a registering mechanism therein, pins connected with the registering devices, means for supporting removable cards and a sheet in front of said pins; and means for causing the pins to punch the sheet and embed the parts punched therefrom into the card.
- 40 4. In a recording device for registers, the combination of a casing, a registering mechanism therein, pins connected with the registering devices, means for supporting a removable card and a sheet in front of said pins, and means for causing the pins to punch the sheet and embed the parts punctured from the sheet into the card, and means for returning the registering devices to zero after each recording operation.
- 50 5. In a card recording device for registers, the combination of a registering mechanism provided with indicating fingers, pins on said fingers, a card or sheet holder opposite said fingers, means for relatively moving the registering mechanism and holder to punch cards placed between said holder and registering mechanism upon said pins, compressible cushions on said pins for disengaging them from the cards, and means for returning the registering devices to zero after each recording operation.
- 60 6. The combination of a registering mechanism having indicating fingers provided with punching pins, a card holder opposite said punching pins, a slidable cam bar for producing relative movement between the holder and the registering mechanism to impale the cards upon said pins, a locking device for said bar, and means for auto-

matically disengaging the locking device from the bar when a card is inserted in position.

7. The combination of a registering mechanism having indicating punching pins, a card holder opposite said pins, means for producing relative movement between the record holder and the registering mechanism to impale a card upon said pins, a rock shaft for operating said means, an operating lever, and means for locking the rock shaft to the lever during part of one movement of the lever.

8. The combination of a registering mechanism having indicating punching pins, a card holder opposite said pins, means for producing relative movement between the record holder and the registering mechanism to impale a card upon said pins, a rock shaft for operating said means, an operating lever, a segment on said rock shaft beside the lever adapted to be engaged thereby during part of the movement of the lever, and a catch for locking the segment to the lever during part of the return movement of the lever.

9. In a card recording device for registers, the combination of a registering mechanism provided with indicating pins, a card holder opposite said pins, means for relatively moving the registering mechanism and card holder to impale the cards upon said pins, means for disengaging the pins from the cards, means for resetting the registering mechanism to zero, and card controlled means for holding the resetting mechanism out of operative position during the puncturing operation.

10. The combination of a registering mechanism having indicating pins, a card holder opposite said pins, means for producing relative movement between the card holder and the registering mechanism to mark the card by said pins, a locking device for said means, and means for disengaging the locking device when a card is inserted in position; with a rock shaft, an operative lever, and means to lock the lever to said rock shaft during part of the movement of the lever.

11. The combination of a registering mechanism having indicating puncturing pins, a card holder opposite said pins, a slidable cam bar for producing relative movement between the record holder and the registering mechanism to impale cards upon said pins, locking devices for said bar, and means controlled by the card for disengaging the locking device from the bar when the card is inserted in position; with a rock shaft operatively connected with said cam bar, an operating lever, a segment connected to said rock shaft beside the lever and adapted to be engaged thereby during part of the movement of the lever, and a locking device for said bar, and means for automatically disengaging the locking device from the bar when a card is inserted in position.

catch for locking the segment to the lever during part of the return movement of the said lever.

12. The combination of a registering mechanism having indicating punching pins, a card holder opposite said punching pins, means for producing relative movement between the holder and the registering mechanism to impale the cards upon said pins, and means for resetting the registering mechanism to zero; a locking device for said means, and devices controlled by the card for disengaging the locking device from the bar when the card is inserted in position; and means for holding the resetting mechanism out of operative position during the puncturing operation.

13. The combination of a registering mechanism having indicating pins, a card holder opposite said pins, means for producing relative movement between the holder and the registering mechanism to mark the cards, locking devices for said means, and means controlled by the card for disengaging the locking devices when the card is inserted in position; a rock shaft operatively connected with said cam bar, an operating lever, means for causing said lever to operate the shaft during parts of its swinging movements; means for resetting the registering mechanism to zero, and means for holding the resetting mechanism out of operative position during the recording operation.

14. The combination of a registering mechanism having indicating punching pins, a card holder opposite said puncturing pins, means for producing relative movement between the holder and the registering mechanism to impale the cards upon said pins, locking devices for said means, and means controlled by the card for disengaging the locking devices when the card is inserted in position; a rock shaft operatively connected with said cam bar, an operating lever, means for causing said lever to operate the shaft during parts of its swinging movements; means for resetting the registering mechanism to zero, and card controlled means for holding the resetting mechanism out of operative position during the puncturing operation.

15. The combination of a registering mechanism having indicating fingers provided with pins, a card holder opposite said pins, a slideable cam bar for producing relative movement between the card holder and the registering mechanism, a rock shaft operatively connected with said cam bar, a lever pivotally connected on said shaft, and means for causing said lever to operate the shaft during part of its swinging movement; a segment connecting said rock shaft beside the lever and adapted to be engaged thereby during part of the movement of the lever, a catch for locking the segment to

the lever during part of the return movement of the said lever; means for resetting the registering mechanism to zero; and means for holding the resetting mechanism out of operative position during the puncturing operation.

16. The combination of a registering mechanism having indicating fingers provided with pins, a card holder opposite said pins, a slideable cam bar for producing relative movement between the card holder and the registering mechanism, locking devices for said bar, and means controlled by the card for disengaging the locking device from the bar when the card is inserted in position; with a rock shaft operatively connected with said cam bar, a lever pivotally connected on said shaft, and means for causing said lever to operate the shaft during part of its swinging movement; a segment connecting said rock shaft beside the lever and adapted to be engaged thereby during part of the movement of the lever, and a catch for locking the segment to the lever during part of the return movement of the said lever.

17. The combination of a registering mechanism having indicating fingers provided with punching pins, a card holder opposite said puncturing pins, a slideable cam bar for producing relative movement between the record holder and the registering mechanism to impale the cards upon said pins, locking devices for said bar, and means controlled by the card for disengaging the locking device from the bar when the card is inserted in position; with a rock shaft operatively connected with said cam bar, a lever pivotally connected on said shaft, and means for causing said lever to operate the shaft during part of its swinging movement; a segment connecting said rock shaft beside the lever and adapted to be engaged thereby during part of the movement of the lever, a catch for locking the segment to the lever during part of the return movement of the said lever, means for resetting the registering mechanism to zero, and means for holding the resetting mechanism out of operative position during the puncturing operation.

18. The combination of a casing adapted to hold a card, a registering mechanism, means for transferring the record of said registering mechanism to said card, and means for recording the readings of said mechanism; a resetting gear on the registering mechanism, a pivoted lever beside the resetting gear, a gear on said pivoted lever adapted to engage the resetting gear, and means for operating said gear.

19. The combination of a casing adapted to hold a card, a registering mechanism having punching pins and means for impaling a card on said pins; a resetting gear on the registering mechanism, a pivoted lever be-

side the resetting gear, a gear on said pivoted lever adapted to engage the resetting gear, and means for operating said gear; with devices for holding said resetting gear 5 out of operative position when the parts are in normal registering position.

20. The combination of a casing adapted to hold a card, a slidable frame in said casing, a registering mechanism mounted in 10 said frame and having pins adapted to mark a card, means for moving said frame, a rock shaft and connections for operating said means, an operating lever; with a resetting gear on the registering mechanism, 15 a pivoted lever beside the resetting gear, a gear on said pivoted lever adapted to engage the resetting gear, and means for operating said gear, and devices for holding the gear out of operative position when the lever 20 and parts are in normal registering position.

21. The combination of a casing adapted to hold a card, a slidable frame in said casing, a registering mechanism mounted in said frame and having punching pins on its 25 fingers adapted to puncture the card, means for moving said frame, a rock shaft and connections for operating said means, an operating lever, a segment on said rock shaft adapted to be engaged by said lever on one 30 part of its swinging movement, and a catch for locking the lever to the cam bar during part of its return movement; with a resetting gear on the registering mechanism, a pivoted lever beside the resetting gear, a 35 gear on said pivoted lever adapted to engage the resetting gear, means for operating said gear, and devices controlled by the card for holding the gear out of operative position when the lever and parts are in normal 40 registering position.

22. The combination of a registering mechanism having indicating fingers provided with punching pins, a card holder opposite said pins and a slidable cam bar 45 and coöperating means whereby the holder and the registering mechanism are relatively moved so as to cause said pins to punch the card.

23. In a recording mechanism, the combination of a casing adapted to have cards inserted therein, registering and card impressing means movably mounted in the casing, a lever and connections to actuate said movable means to impress the cards, a second 55 means for impressing the cards, a second lever connected to the second means, and operative connections between the said levers.

24. In a recording mechanism the combination of a casing adapted to have cards 60 inserted therein, a frame movable in the casing, registering and card impressing means mounted on the movable frame, means for

actuating the movable frame to impress the cards, and an independent card impressing means operable by said frame actuating 65 means.

25. In a recording mechanism the combination of a casing adapted to have cards inserted therein, a frame movable in the casing, registering and card impressing means 70 mounted on the movable frame, a lever and connections for actuating said movable frame to impress the cards, and a plunger having card impressing means connected to be operated from said lever mechanism. 75

26. In a recording mechanism, the combination of a casing adapted to have cards inserted therein, a frame movable in the casing, registering and card impressing means 80 mounted on the movable frame; a lever and connections to actuate said movable frame to impress the cards, a plunger having means for impressing the cards, a cam lever connected to the plunger, and operative connections between the cam lever and said first 85 lever.

27. In a recording mechanism the combination of a casing adapted to have cards inserted therein, a frame movable in the casing, registering and card impressing means 90 mounted on the movable frame, means for operating the movable frame to impress the cards, a plunger having means for impressing the cards, a cam lever pivoted on the 95 casing, a link connecting the cam lever and the plunger; and means for operating the cam lever from the frame actuating means.

28. In a recording mechanism the combination of a casing adapted to have cards inserted therein, a frame movable in the casing, registering and card impressing means 100 mounted on the movable frame, means for operating the movable frame to impress the cards, a plunger bearing means for impressing the cards, a block slidably mounted on 105 the casing and carrying said plunger, and operative connections between the plunger and said frame actuating means.

29. In a recording mechanism the combination of a casing adapted to have cards 110 inserted therein, a frame movable in the casing, registering and card impressing means mounted on the movable frame, means for operating the movable frame to impress the cards, a plunger having means for impressing the cards, a block slidably mounted on the casing and carrying said plunger, a cam lever pivoted on the casing, a link connecting the cam lever with the plunger, and operative connections between said cam lever 115 and its frame actuating means.

In testimony that I claim the foregoing as my own, I affix my signature.

JOSEPH H. WEEKS.
